UNITED STATES PATENT OFFICE.

EDWARD J. OVINGTON, OF AUBURNDALE, MASSACHUSETTS, ASSIGNOR TO DAVIS & GECK, INC., OF BROOKLYN, NEW YORK, A CORPORATION OF NEW YORK.

SUTURE.

Application filed March 5, 1923. Serial No. 622,780.

To all whom it may concern:

Be it known that I, EDWARD J. OVINGTON, a citizen of the United States, and resident of Auburndale, in the county of Middlesex 5 and State of Massachusetts, have invented an Improvement in Sutures, of which the following description, in connection with the accompanying drawings, is a specification, like letters on the drawings representing like 10 parts.

My present invention is an improvement in surgical needles known as sutures and an important and novel process of manufacturing the same.

15 In the manufacture of sutures for surgical work it is of great importance that the needle and the ligature should be united in a manner to eliminate, to the greatest degree possible, any sharp angles, rough 20 surfaces, protuberances, recesses, or openings, as well as to prevent discrepancies in size between the needle and the ligature. The ideal condition would be to have the 25 suture of continuous metal, with the ligature connected therewith in the same flush plane and independent of any openings, recesses or the like, and this has been impossible of attainment in the prior art. My 30 present invention approximates this ideal result more nearly than any prior article, and my method of so forming the needle and connecting the ligature presents a substantially continuous surface from the needle to the ligature entirely independently 35 of recesses, rough surfaces, sharp angles or the like, or a weakened place, and while also maintaining full strength of the metal at every point in the needle. This latter feature is of great importance and is a distinct 40 novelty with me.

In carrying out my invention, I first form the needle in a novel method, utilizing a die which will swage, stamp or flatten the end portion opposite the point of the needle 45 blank or bar into suitable and predetermined shape to permit the wrapping or folding up of the swaged or stamped part to encircle the inserted portion of the ligature and then uniting the opposite edges of the 50 stamped, swaged or flattened part so as to join the same in a substantially single continuous line. It will be appreciated that each time a suture is used it is discarded and therefore a new needle and new ligature 55 must be united for every operation, and con-

sequently a simple, efficient and practicable method of effecting this union of the needle and ligature, producing a uniform result, is of great importance.

Referring to the drawings, illustrating 60 my novel method, and the improved suture resulting therefrom,

Fig. 1 is a plan view shown on enlarged scale of a needle blank or bar;

Fig. 2 is a side view illustrating the needle 65 blank or bar after the first process of flattening a portion of the same has been carried out;

Fig. 3 is a plan view of the needle as shown in Fig. 2;

Fig. 4 is a side view partly in cross-section after the flattened portion of the needle has been rolled upwardly into ligature receiving position;

Fig. 5 being a corresponding top or plan 70 view of the same;

Fig. 6 is a view partly in cross-section, showing the ligature in position and the opposed edges of the flattened portion curved, curled or forced over into abutting 80 alinement;

Fig. 7 is a top or plan view of the completed suture;

Fig. 8 is a cross-sectional view on the line 8—8 of Fig. 7;

Fig. 9 is an end view of the blank as shown in Fig. 3; and

Fig. 10 is an end view of the blank as illustrated in Fig. 5.

While the drawings illustrating my invention are on an enlarged scale, it will be appreciated that the same can be applied to and carried out upon needles of any size or diameter with equal facility. The needle bar or blank 1 is first subjected to a swaging, 90 forming or flattening action, at the rear portion. This feature is readily accomplished by placing the rear portion in appropriate position under a die shown in dotted lines at 2. This die is so shaped as to cause the metal of the needle blank or bar to be forced out during the swaging operation into such form that the edges of the swaged portion, when wrapped about a ligature, will substantially meet throughout their length. 100 As more clearly shown in dotted lines in Fig. 2, the die 2 is formed with a beveled portion at one end which, when in operative position is directed toward or faces the pointed end of the needle bar or blank 1. 105

The said beveled end portion converges into a line 3, which, in the swaging operation, forms the forward inclined or beveled wall or end 4 of the swaged portion of the needle as shown in Fig. 4, and at the same time forces the edges of the metal of the needle bar or blank adjacent the said inclined or beveled wall 4, to assume the complementary cooperating curves 7, which edges converge and merge into the body proper of the needle bar.

The operation of this action will be readily appreciated. The rearmost part of the needle is positioned under the die 2, and thereupon the die 2 is brought in contact with the needle, whereupon the needle is automatically held, or grasped and the continued downward movement of the die upon the end portion of the blank results in swaging, forming or flattening out this portion into the contour as shown at 6, Figs. 2, 3 and 9. During this forming or flattening action the metal in the forward portion will flow around the sharpened and beveled end 3 of the die 2, forming the swaged edges on complementary cooperating curves 7 between the front end 4 and the edges 8 and 9 respectively of the flattened blank, and which curved edges converge and merge into the body proper of the needle bar. This contour is of great importance as it must be properly proportioned to permit the subsequent wrapping or folding of the sides 8 and 9 around the ligature 12 and resulting substantially in a meeting or alinement of the edges 8 and 9 and the two curved portions 7 throughout their length in a completed article, as illustrated in the abutting edges 15 in Figs. 7 and 8. I accomplish this result by a proper formation of the die 2. With the blank formed as illustrated at 3, I then fold up the edges 8 and 9, and the two curved portions 7—7 respectively, substantially as illustrated at Figs. 4, 5 and 10. The needle is now ready to receive the ligature 12, the end of the same being fitted within the partially curved sides 8 and 9, whereupon the union of the ligature and needle is completed by setting the edges 8 and 9 and the two curved portions into completely curved position, clamping the same in a suitable die, thus uniting the edges tightly around the ligature 12 until the opposed edges 7, 7 and 8 and 9 meet in a substantially straight line 15, as clearly shown in Fig. 7. If desired, this final action may be sufficient in extent to slightly countersink the metallic portions of the needle around, about and into the suture 12, as shown at 20, Figs. 6 and 7, thus forming both needle and ligature into a suture of uniform diameter. The resulting article produces a suture without rough edges, openings, recesses or the like, to be objectionable, or other objectionable features, while

affording a complete suture with the needle and ligature of uniform diameter. The meeting edges in the line 15 are in direct alinement with the diameter of the needle and the frictional engagement of this portion of the needle on the ligature and the countersinking therein if desired, insures a firm, strong, union under substantially ideal conditions.

My invention can be utilized for straight needles, curved needles, liver needles, or any other surgical instrument wherein a connection between the needle and sewing thread or ligature is desired.

The process enables the full metallic strength of the needle to be practically preserved at the point of junction of the needle and ligature, thus eliminating a weak joint or point and thereby obviating the danger of breakage.

My invention is further described and defined in the form of claims as follows:

1. A needle having one end swaged to provide free portions the adjacent edges of which converge and merge into the body proper of the needle and which may be brought into substantial contact throughout their length when wrapped about a ligature.

2. A suture, comprising a needle having its rear end portion swaged so that the edges of the swaged part adjacent the body of the needle are formed upon complementary cooperating curves such that when the swaged portion is rolled, the edges substantially meet throughout their length and close the opening from the body of the needle to the end thereof; and a ligature, one end of which is attached to said swaged portion of the needle, the swaged portion of the needle being wrapped about the ligature.

3. As a new article of manufacture, a surgical needle having its rear end portion swaged into a thinner part the edges of which adjacent the body of the needle are formed upon complementary curves leaving a thickness of metal in that part of the swaged portion adjacent the needle greater than that in the remainder of the swaged portion, the shape of the edges being such that they substantially meet throughout their length when rolled into approximately cylindrical form; whereby the junction of the body of the needle and the swaged portion has its strength preserved.

4. The improvement in the art of forming needles for surgical uses, which consists in swaging the rear end of the needle bar with a die so shaped as to cause the metal to be forced out into such a form that the edges of the swaged portion when wrapped about a ligature will substantially meet throughout their entire length.

In testimony whereof, I have signed my name to this specification.

EDWARD J. OVINGTON.
